UNITED STATES PATENT OFFICE.

CHARLES O. I. NILSSON, OF BROCKTON, MASSACHUSETTS.

BEET-HARVESTER.

1,134,221.

Specification of Letters Patent.

Patented Apr. 6, 1915.

Application filed June 22, 1914. Serial No. 846,668.

To all whom it may concern:

Be it known that I, CHARLES O. I. NILSSON, a citizen of the United States, residing at Brockton, in the county of Plymouth and State of Massachusetts, have invented certain new and useful Improvements in Beet-Harvesters, of which the following is a specification.

My invention relates to improvements in beet harvesters and resides in the provision of an extremely effective and reliable device that will gather beets from the rows, sever the tops therefrom and dispose the beets into a receptacle and the tops on the ground, in an expeditious manner.

Another and more specific object is to provide a beet harvester which comprises a wheel supported frame carrying means to dig and elevate the beet to a point where the tops are severed therefrom; also means for topping the beets.

Another object of my invention is to provide elevating means that are adjustable in various ways so as to be suited for operation in connection with beets of different sizes.

Another object is to provide novel gearing means for operating the elevating means that are adjustable so as not to be interfered with when the elevating means are adjusted and the proper elevating of the beets at the proper time is insured.

Another object of importance is to provide a beet harvester of the character described that is of exceedingly simple construction and is light, strong and durable, may be cheaply manufactured and is inexpensive to maintain in working condition.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts:

Figure 1 is a longitudinal sectional view partly in elevation of my improved beet harvester, showing the same in assembled and operative position. Fig. 2 is a top plan view. Fig. 3 is a detail sectional view of the gearing to operate the elevating means. Fig. 4 is a fragmentary detail sectional view of the adjusting gearing at the upper ends

of the elevator bars. Fig. 5 is a transverse sectional view taken on the plane of line 5—5 of Fig. 1, illustrating the means for operating the topping knife and showing parts of the elevating mechanism. Fig. 6 is a transverse sectional view taken at the forward end of the harvester, showing the means for loosening the soil about the beets so that they may be readily pulled from the rows by the tops.

Referring to the drawings by characters of reference the numeral 1 designates as an entirety the vehicle body or frame having mounted adjacent its ends, front and rear axles 2 and 3 respectively that have wheels 4 on their ends. Suitable draft gear designated 5 as an entirety is operatively connected with the platform or frame 1. A driver's seat 5^a of the usual type is mounted on the frame 1.

The frame 1 consists of two parts, a rear part A and forward part B. The part B carries all of the mechanism except the receptacle to contain the topped beets so that the device may be turned at the end of a row as will be later more fully described. An angular bearing C is secured adjacent the forward edge of the rear part A and pivoted by means of a bolt D to the rear part of the frame B as clearly shown in Fig. 1 in the drawings. A block E spaces the bearing C from the frame part B so that free turning of the part B relative to the frame part A is provided.

Mounted on the frame 1 and extending upwardly and rearwardly therefrom are spaced and parallel elevator bars 6 and 7 that are supported intermediate and approximately centrally of their ends by forwardly and upwardly inclined screw threaded adjusting rods 8 that are inserted through screw threaded sleeves 9 rigidly secured in the bars 6 and 7 and having operating handles 10 fixed on their outer ends. The lower ends of the rods 8 are grooved circumferentially, as at 11, and positioned within angularly disposed sockets 12, that are slidably supported on the frame 1 by means of angle guides 12' that are secured by suitable fastening means to the frame and engage the upper faces of the flanges 12" that act as bases for the sockets. A holding screw or bolt 13 is inserted through the intermediate portion of each socket and at its inner end engages within the groove 11 in the rods 8. It will be readily seen that the bars 6 and 7

may be adjusted in an approximately vertical plane so that the lower ends thereof are spaced in inoperative relation to the ground.

5 The bars 6 and 7 are also supported at points adjacent to the rods 8 but slightly spaced and arranged rearwardly therefrom on a horizontal adjusting rod 14. This rod 14 is adjustable in a pivoted link bracket 10 15 that is pivotally secured to an upstanding support 15' carried by the frame 1. A receptacle 16 is mounted on the body to catch the beets that are topped. A handle 17 is fixed on one end of the adjusting rod 14 to permit adjustment of the bars 6 and 7 laterally or to and from each other. It will 15 20 be readily seen that the rod 14 acts as a pivot and that in operating the adjusting rods 8 the forward ends of the bars 6 and 7 will be lifted upwardly.

20 The forward ends of the bars 6 and 7 are curved upwardly and outwardly, as at 18, so as to slide over the surface of the ground. Slightly curved and elongated fingers 19 25 are arranged at the extreme forward end of the bars 6 and 7 and extend outwardly in a slightly convergent plane and are designed to slide over the ground on opposite sides of a row of beets so as to clear the beets that are to be gathered and elevated to the topping knives, of trash and other foreign matter. As a means for loosening the beets in the rows so that they may be readily gripped at the top and pulled from the ground I provide digging fingers 20 that are curved inwardly toward one another at their lower ends, as at 21, and secured upon the inner faces of the bars 6 and 7 adjacent to the lower ends of said bars. Fingers 20 30 35 are slideable in suitable brackets 22 secured upon the inner faces of the bars 6 and 7 and are adjustable so as to dig into the ground at different depths. As a means for adjusting the fingers 20 I provide a bell lever 23 that is provided with suitable locking mechanism designated 24 as an entirety and has its larger arm portion 25 pivotally connected with the upper ends of the fingers 20 as at 26. I provide a lever 23 and coöperating 40 45 50 parts for each of the fingers 20.

50 The elevating mechanism comprises a plurality of sprockets 27 that are journaled for rotation in transverse recesses 28 formed in the bars 6 and 7. The sprockets that are 55 arranged at the ends and central portions of the bars 6 and 7 have mounted thereon elevating chains 29 and are so disposed at their inner sides as to grip or clamp the tops of the beets therebetween sufficiently 60 to hold the beets and elevate them to the topping mechanism, to be later described. The sprockets 27 are of such size as to extend the chains 29 in close proximity to one another on certain sides of the chain to effect the action described.

The centrally arranged sprockets 27 on the bars 6 and 7 are splined on substantially upright shafts 30 that are mounted in the bars 6 and 7. These shafts 30 extend downwardly below the under faces of the bars 6 and 7 and are slideable with relation thereto, the upper end of each shaft being arranged so as to prevent its pulling out of the bars. Keyed on the lower end of the shaft 30 is a bevel gear 31 that meshes with the bevel gear 32 which is splined on a horizontal shaft 33. The horizontal shaft 33 is arranged in superposed parallel relation to the forward axle 2 of the device and is provided at its outer end with a pinion 34 keyed thereon and which meshes with a larger gear 35 mounted on the axle 2. The shaft 33 is journaled in suitable bearing brackets 36 that are secured to the frame or platform 1, and is also supported by means of an angular arm 37 that on its lower end is operatively connected with a cylindrical extension 38 which is formed integral with the gear 32. The projection 38 is provided with a key groove to receive the keys on the shafts so that the gear 32 is splined and is slideable horizontally on the shaft. The upper end of the arm 37 is provided with a pin and slot connection designated 39 as an entirety with the outer side faces of the bars 6 and 7. The pin and slot connection 39 permits the vertical or approximately vertical adjustment of the bars 6 and 7. The lateral adjustment of the bars 6 and 7 will not interfere with the operating mechanism for the elevator chains 29 inasmuch as the gear 32 is slideable upon its shaft and is connected by the arm 37 with the bars 6 and 7. Thus the gear 32 is caused to slide in accordance with the movement of the gear 31 and held in meshing relation at all times. Brackets 12' described in connection with the sockets 12 for the adjusting rods 8 slideably secure the socket and adjusting rod. It will thus be seen that the adjusting rods 8 are permitted lateral adjustment and the lateral adjustment of the bars is thus not interfered with.

A clutch collar 40 is splined on the front axle 2 and arranged to coöperate with a clutch collar 41 that is mounted on the shaft 2 and secured to the large gear 35. It will be readily seen that when the gears and clutch members 40 and 41 are not engaged the mechanism for elevating the beets will be in inoperative position. To cause the clutch members 40 and 41 to coöperate I provide the operating levers 42 for the clutch members 40 that are provided with forked lower ends fitting within grooves in such clutch members. The operating levers 42 may be suitably connected with the frame and approximately arranged adjacent to the driver's seat so that the driver by grasping one of the levers 42 may cause the clutch 115 120 125 130

member 40 to coöperate with the one 41 resulting in the rotation of the gears and operation of the elevating mechanism.

The topping mechanism comprises a toppling knife 43 that has a number of angularly disposed blades extending radially from the center of the knife and is fixed upon the lower end portion of the vertical shaft 44. The shaft 44 is rotatably journaled at its outer end to a slide bar 45 that is arranged transversely of and slidably secured to the bars 6 and 7 at its end. The end portions of the bar 45 are slotted, as at 46, and receive loosely, fastening means to permit sliding of the bar 45. A gear 47 is keyed upon the lower end of the shaft 44 and meshes with the gear 48 that is keyed upon the lower end of the shaft 49 on which a certain sprocket 27 is mounted. In this connection it will be noted that the shaft sprocket is arranged between the center sprocket and upper sprocket and adjacent to the topping knife 43. The rotation of the knife 43 is brought about through the medium of the shaft 49 and gears 48 and 47.

The operation of my device may be briefly described as follows: Assuming that the device is ready to be drawn along a row of beets, the operator upon manipulation of the rod 42 causes the clutch members 40 and 41 to coöperate and the rotation of the gear for operating the elevating mechanism is had. The digging fingers 20 are arranged at the desired position and loosen the earth along opposite sides of the beets as the harvester is drawn along the row. The extended fingers 19 serve to clear the space about the beets of trash and other foreign matter and prevent entanglement of weeds and sticks in the elevator chains. These fingers 19 serve to guide the beets or tops of the beets in such position that they will pass between the lower ends of the bars 6 and 7 and will be engaged and clamped by the chains 29. The chains 29 and lowermost sprocket 27 are so arranged that the beets or tops thereof will be readily grasped at points above where the tops are joined to the beets. The spacing of the chains 29 relative to each other is regulated by the adjustment permitted the bars 6 and 7. It will be readily seen that this chain is adjustable to suit the sizes of beets that are being worked upon. When the beets are carried upwardly by the chain the topping knife 43, which is so positioned as to sever the tops from the beets at a point below where the top is clasped or clamped by the chain, operates as described and the beet readily drops into a receptacle 16 mounted on the platform 1 that is disposed immediately beneath the topping knife. The top is carried up toward the end of the bars and drops rearwardly of the device upon the ground. To adjust the tension of the chain

I provide at the upper end of each bar a slideable member 50 that is slideable within a recess in which the upper sprocket is mounted. The member 50 is connected with the sprocket and an adjusting screw 51 that is turned in the outer end of the bar and swiveled at its inner end to the member 50. By operating the adjusting screw the slack of the chain may be regulated. It will be noted that when it is desired to lift the digging fingers 20 and coöperating parts in spaced relation to the ground the handles 10 are grasped and the adjusting rod 8 rotated. Upon the rotation of the adjusting rod 8 the bars 6 and 7 will be moved on the bar 14 upwardly so that the lower ends thereof are spaced from the ground and the device may be readily drawn across the field when not operating.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

Having thus described the invention what is claimed as new, is:

1. In a beet harvester a wheel supported frame, means to clamp the tops of beets, withdraw the beets from the ground and elevate them to the topping means whereby the tops are severed, said last named means consisting of spaced parallel upwardly and rearwardly inclined bars mounted on the frame with their lower ends disposed to engage the ground, sprockets in the bars, chains on the sprockets arranged in spaced relation to each other along opposed sides to clamp the tops of beets and remove the beets from the ground and elevate the beets to the topping mechanism, means arranged intermediate the ends of the bars to adjust the bars relative to one another in a lateral plane, and means to move the lower end of the bars away from the ground arranged in connection with the frame and bars at a point forwardly of the means for adjusting the bars laterally, said means for adjusting the bars laterally acting as a pivot for the bars upon vertical adjustment thereof, and said means for adjusting the bars vertically being slideable laterally with relation to the frame.

2. In a beet harvester a wheel supported frame, topping means to sever the tops of beets, means to withdraw the beets from the ground and elevate them to the topping means whereby the tops are severed from

the beets, said last named means including bars arranged in spaced relation to one another and having chains rotatably mounted thereon to grip the tops of beets therebetween, means to adjust the bars in a vertical plane comprising screwthreaded rods clamped to the bars intermediate the ends thereof, handles on the screwthreaded rods, means slidably secured to the frame to secure 10 the adjusting rods, and means to adjust the bars laterally with relation to one another.

3. In a beet harvester a wheel supported frame, topping means to sever the tops of beets, means to withdraw the beets from the ground and elevate them to the topping means whereby the tops are severed from the beets, said last named means including bars arranged in spaced relation to one another and having chains rotatably mounted thereon to grip the tops of beets therebetween, means to adjust the bars in a vertical plane comprising screwthreaded rods clamped to the bars intermediate the ends thereof, handles on the screwthreaded rods, 20 angularly disposed sockets and means secured to the frame to rotatably secure the adjusting rods in the sockets.

4. In a beet harvester a wheel supported frame, means to top the beets, means to clamp the tops of the beets and elevate them to the topping means consisting of bars arranged in spaced parallel relation to one another and upon the frame, sprockets mounted within the bars, chains mounted on the sprockets and arranged to clamp the tops of the beets, means to rotate the same, a bar adjustable transversely of the first named bars, a depending shaft rotatably journaled in the last named bar, and supporting the topping means, a gear on the lower end of said shaft, and a gear operatively connected with one of the sprockets connected with said last named gear, and

means to adjust the bars to and from one another in a lateral plane.

5. In a beet harvester including a wheel supported frame having means to top the beets, means to grasp the tops of the beets and elevate them to the topping means consisting of bars arranged in spaced parallel relation to one another and upon the frame, sprockets mounted within the bars, chains mounted on the sprockets and arranged to clamp the tops of the beets, means to rotate the chains, a bar adjustable transversely of the first named bars, a depending shaft rotatably mounted in the last named bar, and supporting the topping means, a gear on the lower end of said shaft, and a gear oppositely connected with one of the sprockets connected with said last named gear, and means to adjust the bars to and from one another in a lateral plane.

6. A beet harvester including a wheel supported frame, topping means, means to grasp the tops of beets, withdraw them from the ground and elevate them to the topping means consisting of spaced bars and means to clamp and elevate the beets supported upon the bars, and means to operate said last named means comprising a plurality of gears operatively connected with said means and one of the wheels of the frame, means slidably connecting certain of the gears with the bars whereby the gears are moved relative to the movement of the bars and retained in meshing relation to one another, means to adjust the bars laterally to and from one another, and means to adjust the bars vertically.

In testimony whereof I affix my signature in presence of two witnesses.

CHARLES O. I. NILSSON.
